UNITED STATES PATENT OFFICE.

JOHN E. KALGREN, OF MINNEAPOLIS, MINNESOTA, ASSIGNOR TO THE J. R. CLARK CO., OF MINNEAPOLIS, MINNESOTA, A CORPORATION OF MINNESOTA.

IRONING BOARD.

Application filed September 17, 1927. Serial No. 220,272.

My present invention relates to ironing boards and provides an ironing board that is of simple construction, easily set up and taken down, which is very rigid when set up, and which may be folded into a minimum of space, thereby adapting a large number thereof to be shipped as a carload.

In the accompanying drawings, which illustrate the invention, like characters indicate like parts throughout the several views.

Referring to the drawings:

Fig. 1 is a perspective showing the improved board set up for use;

Fig. 2 is a longitudinal vertical section taken through the board on the line 2—2 of Fig. 1;

Fig. 3 is a bottom plan view of the board, showing the same taken down or folded into flat forms;

Fig. 4 is a transverse vertical section taken approximately on the line 4—4 of Fig. 2, some parts being shown in full;

Fig. 5 is a fragmentary section taken on the line 5—5 of Fig. 1;

Fig. 6 is a fragmentary section taken on the line 6—6 of Fig. 3, but showing the parts in the positions that they occupy when the board is set up for use;

Fig. 7 is a fragmentary vertical section taken approximately on the line 7—7 of Fig. 1; and

Fig. 8 is a fragmentary view in perspective showing the free end of what may be designated as the inclined top brace of the ironing board.

The chief elements of this ironing board are the top board 7, the rear legs 8, the inclined third leg 9, the inclined top brace 10 and the bottom brace 11. The rear legs 8 are pivoted to the rear end of the board 7, and as a highly efficient means for affording this pivotal connection, a strap-like metal anchor bracket 12 is riveted or otherwise rigidly secured to the bottom of said board and is provided with obliquely downturned ends 12^a that afford hinge lugs. Supplemental hinge lugs 12^b are riveted, welded or otherwise rigidly secured to the strap 12 and extend parallel to the cooperating lugs 12^a from which they are slightly spaced, so as to permit the legs 8 to be inserted between the said lugs and to be pivotally connected thereto by pin rivets or bolts

13. The oblique lugs on the opposite sides 55 of the board flare downwardly from each other so that the legs 8, when turned down, will be given a spread and their lower ends engaged with the floor a distance greater than the width of the board and when the 60 legs 8 are folded against the bottom of the board, said legs will be parallel and rest within the transverse dimension of the board. These two relative positions of the 65 legs 8 are clearly illustrated in Figs. 1 and 3.

To prevent excessive spread by lateral springing of the legs 8 when said legs are turned down, there is provided a pair of rod-like rear leg braces 14, the upper ends of which are passed through and loosely 70 pivoted to an anchor 15 shown as in the form of a U-shaped metal strap rigidly secured to the bracket-forming strap 12. The lower ends of the brace rods 14 are passed freely through stop lugs 16 shown as in the form of angle pieces riveted to the legs 8 at their intermediate portions. The extreme ends of the rods 14 are upset or formed with heads and the arrangement 75 is such that when the legs 8 are folded against the board 7, the lower ends of the brace rods 14 will move slightly but freely through the lugs 16.

This ironing board has three supporting legs, to wit: the two legs 8 and the inclined 85 leg 9. This leg 9, at its upper end, is pivotally connected to bracket-like lugs 17 riveted or otherwise rigidly secured to the bottom of the board 7 at a point that is preferably slightly forward of the rear leg 80 pivots.

The inclined top brace 10 is a bifurcated or two-part member shown as composed of two straight bars tied together at their free ends by a link 18 and at their lower rear ends 85 pivotally connected one to each leg 8 by a pivot bolt or rivet 19, which also pivotally connects to the inner side of the corresponding leg 8 a channel-shaped guide head 20. The bottom brace 11 is a bifurcated member 100 in the form of a heavy wire or light rod, the arms of which work freely through aligned perforations in the respective channel-shaped guide heads 20, and at the rear thereof are formed with stop heads 21. The 105 front portion of this brace 11 embraces the lower end of the inclined leg 9 and the bow thereof is pivotally connected thereto, being

preferably seated in a notch formed therein and secured to said leg by a U-shaped staple 22.

The board is set up by pressing the free end of the top brace 10 into interlocking engagement with a stop cleat or strip 23 rigidly secured to the bottom of the board 7; and when the parts are thus set up, the arms and the braces will be put under tension or 10 stress so that they will rigidly support the board. The rear legs 8, because of their pivots, will be spread when turned down, and under the weight of the board, will tend to further spread, but the spreading movement 15 thereof will be positively limited by the rear leg braces 14. A yielding element such as a rubber button 24, best shown in Fig. 6, is applied to the short upper end of the inclined leg 9 and, by engagement 20 with the bottom of the board, compensates for variations in the adjustments of the legs and braces. The arms of the bottom brace 11, at their rear ends, are formed with stop heads 11^a that engage the guide heads 20 so 25 as to cause the brace 11 to be put under tensile strain when the board is set up. The guide heads are preferably pivotally connected directly both to the rear legs and to the top brace, but from a broader point of 30 view, the arms of the bottom brace are mounted for pivotal and sliding movement in respect to said rear legs and top brace.

Obviously, the board may be quickly set up, quickly folded, when set up will be very 35 rigid, and when folded will be in flat formation and within a minimum of space.

What I claim is:

1. The combination with a board, of rear legs pivoted to the rear end of said board, a 40 third leg pivoted to said board and forwardly inclined in respect to said rear legs, a top brace pivotally connected to said rear legs and arranged to be detachably secured to the bottom of said board at its free end, 45 guide heads pivotally mounted on said rear legs, and a bottom brace pivotally connected to the lower end of said inclined third leg and having arms supported by and arranged to slide through said pivoted guide heads 50 and which are put under tension when said top brace is secured to the board.

2. The combination with a board, of rear legs pivoted to the rear end of said board, a third leg pivoted to said board and forwardly inclined in respect to said rear legs, a top brace pivotally connected to said rear legs and arranged to be detachably secured to the bottom of said board at its free end, 55 guide heads pivotally mounted on said rear legs, and a bottom brace pivotally connected to the lower end of said inclined third leg and having arms supported by and arranged to slide through said pivoted guide heads 60 and which are put under tension when said top brace is secured to the board, said guide 65

heads, rear legs and top brace being pivotally connected by a common pivot at each side of the board.

3. The combination with a board, of rear legs pivoted to the rear end of said board, a 70 third leg pivoted to said board and forwardly inclined in respect to said rear legs, a top brace pivotally connected to said rear legs and arranged to be detachably secured to the bottom of said board at its free end, 75 guide heads pivotally mounted on said rear legs, a bottom brace pivotally connected to the lower end of said inclined third leg and having arms supported in and arranged to slide through said guide heads and which are 80 put under tension when said top brace is secured to the board, and rear leg braces connected to said legs at their lower ends and at their upper ends pivotally connected by pivots that are approximately axially 85 aligned with both rear leg pivots.

4. The combination with a board, of rear legs pivoted to the rear end of said board, a third leg pivoted to said board and forwardly inclined in respect to said rear legs, 90 a top brace pivotally connected to said rear legs and arranged to be detachably secured to the bottom of said board at its free end, guide heads pivotally mounted on said rear legs, a bottom brace pivotally connected to the lower end of said inclined third leg and having arms supported in and arranged to slide through said guide heads and which are 95 put under tension when said top brace is secured to the board, 100 downwardly flared hinge lugs secured to said board, said rear legs being pivotally connected to said lugs whereby said legs will be spread when turned down and will be moved closer together when turned up against the board, and rear leg braces set at an angle to said rear legs, 105 slidably connected to said rear legs at their lower ends and at their upper ends pivotally connected to said board by pivots approximately axially aligned with the rear leg 110 pivots.

5. The combination with a board, of an anchor bracket rigidly secured to the bottom of the rear end portion thereof and formed at each end with spaced downwardly diverging hinge lugs, rear legs each pivoted between a pair of said hinge lugs and arranged to be spread when turned downward, rear leg braces extended at an angle to said legs and slidably connected to said legs at their 120 lower ends and at their upper ends pivotally connected to said bracket by pivots approximately axially aligned with both rear leg pivots, a third leg pivoted to said board, and braces co-operating with said legs and 125 said top to hold said top in approximately horizontal position.

6. The combination with a board, of an anchor bracket rigidly secured to the bottom of the rear end portion thereof and formed 130

at each end with spaced downwardly diverging hinge lugs, rear legs each pivoted between a pair of said hinge lugs and arranged to be spread when turned downward, rear leg braces extended at an angle to said legs and slidably connected to said legs at their lower ends and at their upper ends pivotally connected to said bracket by pivots approximately axially aligned with both rear leg pivots, a third leg pivoted to said board and inclining forwardly from said rear legs, a bifurcated top brace pivotally connected to said rear legs and detachably secured to said board, and a bifurcated bottom brace pivotally connected to the lower end of said inclined leg and pivotally and slidably connected to said rear legs and top brace and which is put under tension when said top brace is secured to said board. 15

In testimony whereof I affix my signature.

JOHN E. KALGREN.
